THOMAS C. JOHNSON, OF NEW HAVEN, CONNECTICUT, ASSIGNOR TO WINCHESTER
REPEATING ARMS CO., OF NEW HAVEN, CONNECTICUT, A CORPORATION.

BOX-MAGAZINE BOLT-ACTION RIFLE.

1,323,064.

Specification of Letters Patent. Patented Nov. 25, 1919.

Application filed June 25, 1919. Serial No. 306,532.

To all whom it may concern:

Be it known that I, THOMAS C. JOHNSON, a citizen of the United States, residing at New Haven, in the county of New Haven 5 and State of Connecticut, have invented a new and useful Improvement in Box-Magazine Bolt-Action Rifles; and I do hereby declare the following, when taken in connection with the accompanying drawings 10 and the characters of reference marked thereon, to be a full, clear, and exact description of the same, and which said drawings constitute part of this application, and represent, in—

15 Fig. 1 a broken view in side elevation of a rifle constructed in accordance with my invention.

Fig. 2 a view thereof partly in elevation, and partly in transverse section on the line 20 2—2 of Fig. 1.

Fig. 3 a broken view thereof partly in side elevation and partly in vertical, longitudinal, central section.

Fig. 4 a detached reverse plan view of the 25 trigger-guard.

Fig. 5 a detached view in side elevation of the magazine-holder with the magazine- 30 catch removed.

Fig. 6 a reverse plan view thereof.

35 Fig. 7 a detached view in side elevation of the magazine-catch.

Fig. 8 a detached end view thereof, together with its operating-spring.

Fig. 9 a detached plan view of the cartridge platform.

Fig. 10 a rear end view thereof.

Fig. 11 a front end view thereof.

Fig. 12 a broken reverse plan view of the rifle, showing the finger-notches formed 40 in the lower face of the gun-stock to permit the box-magazine to be pulled out in case it sticks.

Fig. 13 a detached view in side elevation of the box-magazine.

45 My invention relates to an improvement in box-magazine bolt-action rifles, the object being to provide a simple, durable and accurate arm constructed with particular reference to the reduction to the minimum 50 of the time and effort required to interchange the magazines in the gun, and also to facilitate single-loading.

With these ends in view, my invention

consists in a gun having as an improved part, a self-contained magazine-holder 55 adapted to be attached as an independent unit to the receiver of the gun and to receive a self-contained box-magazine having its own follower and spring, whereby the gun-stock and receiver may be separated 60 without disturbing the magazine-holder.

My invention further consists in a self-contained magazine-holder adapted to be attached as an independent unit to the receiver of the gun and furnished with an 65 offsetting housing containing a magazine-catch for the retention within the said holder of a self-contained box-magazine having its own follower and spring.

My invention further consists in a box- 70 magazine bolt-action rifle provided in one of the side walls of the butt-stock with a magazine-release located forward of and above the plane of the finger-loop of the trigger-guard.

My invention further consists in a box- 75 magazine bolt-action rifle formed in the lower face of its stock with one or more finger-notches to permit the lower end of the box-magazine to be seized by the fingers 80 for withdrawing it from the gun.

My invention further consists in a box- 85 magazine gun having a magazine-release located in the side of the butt-stock at a point forward of, and above the plane of the finger-loop of the trigger-guard and the said butt-stock having finger-notches located in its lower face at a point close to the said magazine-release for permitting the magazine to be seized by the fingers and 90 withdrawn.

My invention further consists in a box- 95 magazine gun having the forward tang of its trigger-guard bodily upcurved and formed with a magazine-opening to permit the projecting lower end of the box-magazine to be seized by the fingers and withdrawn.

My invention further consists in a fixed 100 cartridge-platform having an opening to receive the upper end of the box-magazine and provide a horizontal floor flush with the upper end of the same.

My invention further consists in a box- 105 magazine bolt-action rifle having certain details of construction and combinations

of parts as will be hereinafter described and pointed out in the claims.

In carrying out my invention as herein shown, I construct a self-contained magazine-holder adapted to be handled and used as an independent unit, and consisting as herein shown, of a front tie 3, a rear tie 4, a right hand plate 5, and a left hand plate 6, the plate 5 being bent outwardly to produce 10 an offsetting housing 7 for the reception of a pivotal magazine-catch 8 which swings upon a pivot 9 and is controlled by a small helical spring 10 the inner end of which is set into a recess 11 formed in the outer wall of the 15 upper end of the said catch. The respective ties 3 and 4 are formed with alined perforated lugs 12 and 13 receiving screws 14 and 15 which pass upwardly through them and into threaded screw-holes in the lower wall 20 of the bore 16 of the receiver 17. As thus constructed and applied, the magazine-holder constitutes an independent unit adapted as such to be applied to and removed from the receiver without reference 25 to any other part of the arm. Under ordinary circumstances, it will be applied to the receiver when the gun is assembled and not thereafter removed, but when removed, should occasion require, it will be removed 30 as a unit. The plates 5 and 6 above referred to are secured to the ties 3 and 4 by means of transverse rivets 18 as clearly shown in Fig. 5. The magazine-holder as thus constructed, contains a vertical magazine passageway 19 which is given a downward and forward curvature by curving the rear wall 21 of the front tie 3 and the forward wall 20 of the rear tie 4, these curved walls being struck on a center located on a 35 line extended from the bottom of the cartridge-chamber 22 of the gun-barrel 23.

The upper end of the passageway 19 of the above described magazine-holder registers with an oblong opening in the bottom 45 wall of the bore 16 of the receiver 17, while the lower end of the passageway 19 registers with a corresponding magazine-opening 25 formed in the bodily upcurved portion 26 of the forward tang 27 of the strap-like 50 trigger-guard which also comprises a finger-loop 28, and a short rearwardly extending tang 29, the guard being held in place by screws 30 passing upward through it into the butt-stock 31 as clearly shown in Fig. 3. 55 A heavy screw 30^a passes upward through the extreme forward end of the forward tang 17 of the trigger-guard, through the butt-stock 31 and into the forward end of the receiver 17 whereby the receiver and 60 butt-stock are attached together. For separating these two major components of the gun it is only necessary to remove the said screw 30^a. By making the magazine-holder as an independent unit and attaching it as 65 such to the receiver, no part of the trigger-

guard is relied upon to contain the magazine as in many structures of the prior art. The trigger-guard of my improved gun consists, as shown, of a piece of strap-iron having a portion of its forward end bodily upcurved for finger-clearance and formed with an opening through which the magazine proper is introduced into and withdrawn from the magazine-holder, which is positioned within the receiver as explained.

For retaining the self-contained crescent-shaped box-magazine 32 in place in the passageway 19 into which it is introduced through the opening 25 in the bow 26, the magazine is provided near the upper end of its right hand wall with an outwardly struck retaining-lug 33 the lower edge of which is engaged by the upper face of the magazine-catch 8 at the point 34 thereon, as seen in Figs. 2 and 8. When it is desired to remove the magazine from the gun, the catch 8 is disengaged from the magazine by means of a magazine-release 35 consisting of a short plunger mounted in a threaded bushing 36 screwed into a transverse opening 37 formed in the right hand side wall of the stock 31 at a point forward of, and considerably above the plane of the finger-loop 38 of the finger-guard. As shown, the magazine-release 35 is provided at its inner end with a flange or shoulder 40 which engages with the inner end of the bushing 36 and limits the outward movement of the magazine-release. By reference to Fig. 12 it will be noticed that a concentric recess 41 formed in the right hand wall of the stock 31, enables the magazine-release to be located flush with the surface of the stock, the aim being to have the exterior of the stock present a smooth surface to the hand. When the release 35 is manually pressed inward, it overcomes the tension of the spring 10, and rocks the magazine-catch so as to disengage the same from the lug 33 of the box-magazine 32 and permit the same to be removed from the gun. 100

The magazine 32 is of such a length that when it is introduced into the gun, as shown in Fig. 2, its lower end projects downwardly through the opening 25 in the bow 26 of the tang 27 but not below the lower face of the gun stock 31 with which its extreme lower end is flush, as shown in Fig. 2, so that the flow lines of the stock are not interrupted but the lower surface of the stock left smooth to the hand. To permit the projecting lower end of the magazine to be seized by the fingers for forcibly pulling it out of the gun in case it does not drop therefrom by gravity when the plunger 35 is pressed inward, I form one or more segmental finger-notches 43 in the lower face of the gun-stock, such notch or notches coinciding with the bow 26 of the tang 27 so as to permit the access of the fingers to the pro- 115 120 125 130

jecting lower end of the magazine. As shown, and preferably, I employ two of these notches and locate them directly opposite each other as clearly seen in Figs. 2 5 and 12.

The magazine release 35 and the bow 26 and notches 43 are located so close together, as shown in Figs. 1, 2 and 12, that the user of the rifle may grasp the magazine for pulling 10 it away from the gun and push with his thumb and pull with his forefinger almost simultaneously in case the magazine does not respond instantaneously to the releasing action of the magazine-release 35.

15 In order to reduce the friction incident to the insertion and removal of the magazine, the curved rearward and forward walls 20 and 21 formed within the magazine-holder for confining and guiding the magazine, 20 have their edges cut away to form clearance-grooves 44 resulting in the production of relatively narrow bearings 45 for the magazine to ride upon, as shown in Fig. 6.

When in position in the gun, the upper 25 end of the box-magazine 32 rises, as described, through the oblong opening 24 in the lower wall of the cylindrical bore or bolt-chamber 16 of the receiver 17, which, as shown, is formed at the forward end of the 30 said bore with a wide transverse loading and ejection opening 46 which provides for the ejection of the spent cartridge as well as for the manual loading of single cartridges into the chamber 22 in the barrel 23. To 35 fill the spaces created between the side, rear and front walls of so much of the magazine as projects upward into the bolt-chamber 16, I prefer to employ what I shall designate as a cartridge-platform 47, shown in Figs. 40 9 to 11 inclusive, this platform having a rounded lower face to fit the bore 16 and being formed with an oblong opening 48 into which the upper end of the magazine rises, but above which it does not project, as 45 clearly shown in Fig. 2, which also shows that the flat upper face of the platform 47 is in the plane of the walls 49 of the receiver as produced by transversely cutting it away to form the loading and ejection opening 50 46. The upper face of the platform 47 and the horizontal walls 49 form, as it were, a horizontal flooring for the bottom of the opening 46, providing a convenient surface on which to manipulate the cartridges when 55 manually inserting them singly into the chamber 22, there being no projecting edges of the magazine to come in contact with the finger and thumb which are thus provided with smooth surfaces to work upon. This 60 flat floor prevents the thumb and finger from being cut in case the user of the arm wishes to load one or more cartridges into the magazine itself by forcing them downward thereinto through the top of the gun. The 65 cartridge-platform 47 is held in place by the

screw 15, also employed to secure the magazine-holder in place in the receiver, as clearly shown in Fig. 3. It is not essential that the upper surface of the platform 47 shall exactly register with the walls 49 of the loading and ejecting opening 46, but they should be substantially on the same level. It will be observed by reference to Fig. 4, that the oblong box-magazine opening 25 in the clearance bow 26 of the tang 27 of the trigger-guard, is formed at the rear end of its right hand wall with an offset 25^a which is provided for the clearance of the magazine-retaining lug 33 of the magazine 32 as the same is inserted into and removed from the 70 gun. The right hand wall 5 of the magazine-holder is formed with a passage 50 leading to the housing 7 for the clearance of the lug 33 of the magazine, while the lower edge of the left hand wall 6 of the 85 holder is cut away as at 51 (Fig. 5) to permit the projecting lower end of the magazine to be seized by the fingers for pulling it out of the gun.

In the foregoing description, I have used 90 the term "self-contained magazine-holder" in the sense of a unitary structure not comprising any other part of the gun and independent of any other part of the gun in its function, *i. e.*, it excludes every other part 95 of the gun and every other function of the gun than that of holding or receiving a true box-magazine. The term "box-magazine" I have used in the sense of a self-contained box-magazine adapted to receive a 100 charge of cartridges and comprising a follower and follower-spring as distinguished from a sheet-metal cartridge-clip or charger which contains neither follower nor follower-spring and, therefore, is dependent 105 upon an extraneous follower and follower-spring forming permanent features of the gun system.

I claim:—

1. A box-magazine bolt-action rifle having a receiver, a butt-stock, and a self-contained magazine-holder adapted to be applied as an independent unit to the receiver, whereby the receiver and butt-stock may be separated without disturbing such holder. 110

2. A box-magazine bolt-action rifle having a self-contained magazine-holder adapted to be introduced into and removed from the gun as a unitary structure and furnished with a laterally offsetting housing containing 120 a magazine-catch.

3. A box-magazine bolt-action rifle having a receiver, a butt-stock and a self-contained magazine-holder adapted to be attached as an independent unit to the receiver to permit the receiver and butt-stock to be separated without disturbing the said holder and the said holder being furnished with a laterally offsetting housing containing a 125 magazine-catch for the retention within the 130

- holder of a self-contained box magazine having its own spring and follower.
4. A box-magazine bolt-action rifle having a receiver, a butt-stock, and a self-contained magazine-holder adapted to be attached as an independent unit to the receiver and having a curved box-magazine passage-way to adapt it to receive a self-contained box-magazine, the front and rear walls of the said holder being curved downwardly and forwardly and flanked on either side by clearance grooves which clear the front and rear edges of the side walls of the inserted box-magazine.
- 15 5. A self-contained magazine-holder adapted to be inserted into and removed from a gun as a unitary structure and comprising side plates and end ties, one of the said side plates being shaped to form a laterally offsetting housing for the reception of a pivotal magazine-catch.
6. A box-magazine bolt-action rifle having a receiver, a butt-stock, and a self-contained magazine holder adapted to be attached to the receiver as an independent unit to permit the receiver and butt-stock to be separated without disturbing the said holder which comprises side plates and end ties, the upper ends of the latter forming fastenings by means of which the holder is secured to the receiver as an independent unit.
7. A self-contained magazine-holder adapted to be introduced into and removed from a gun as a unitary structure and provided upon its right hand side wall with an offsetting housing containing a magazine-catch and furnished with a passage leading into the said housing.
8. A box-magazine bolt-action rifle having a receiver, a butt-stock, and a self-contained magazine-holder adapted to be attached as an independent unit to the receiver to permit the separation of the receiver and butt-stock without disturbing such holder, and the said holder comprising side walls and end ties, one of the side walls being shaped to form a laterally offsetting housing for the reception of a magazine-catch and the other side wall being formed with a finger-clearance cut and the said end ties being shaped to form a curved magazine passage-way and having their upper ends adapted for the attachment of the holder to the receiver to provide for its attachment thereto and removal therefrom as an independent unit.
9. A box-magazine bolt-action rifle having a strap-like trigger-guard the forward tang of which is bodily upcurved to form an upwardly extending clearance-bow having a box-magazine opening.
10. A box-magazine bolt-action rifle having the lower face of its stock formed with a finger-notch and having the forward tang of its strap-like trigger-guard bodily upcurved to form an upwardly extending

clearance-bow containing a box-magazine opening and registering with the said notch in the stock to permit the projecting lower end of the box-magazine to be grasped for its removal.

11. A box-magazine bolt-action rifle having the lower face of its stock cut away to form two finger-notches located opposite each other, and a strap-like trigger-guard secured to the said stock and having its forward end bodily upcurved to form an upwardly extending clearance-bow registering with the said notches and formed with a box-magazine opening.

12. In a box-magazine bolt-action rifle, the combination with a gun-stock formed in its lower face with a finger-notch, of a strap-like trigger-guard the forward tang of which is bodily upcurved to form an upwardly extending clearance-bow registering with the said notch and containing a box-magazine opening, a box-magazine adapted to be introduced into the gun through the said opening, and a magazine-release for holding the magazine in place and for releasing the same, the said release being located close to the said clearance notch and bow to permit the release to be simultaneously operated with the use of the finger-notch and clearance-bow.

13. A box-magazine bolt-action rifle having its receiver formed with a bolt-chamber and with a transverse ejection and loading opening intersecting the forward end thereof, a box-magazine rising into the said chamber when in position in the gun, and a fixed cartridge-platform having an opening for the reception of the upper end of the magazine and located in the bottom of the forward end of the bolt-chamber to form a horizontal platform substantially flush with the upper end of the magazine.

14. In a box-magazine bolt-action rifle, the combination with a receiver having a cylindrical bolt-chamber and a transverse ejection and loading opening intersecting the forward end thereof and having horizontal lower walls, of a box-magazine rising into the said bolt-chamber, and a cartridge-platform having an opening for the reception of the upper end of the magazine, and a rounded lower face to fit the said bolt-chamber, the top of the platform being substantially flush with the horizontal walls of the ejecting and loading opening.

15. In a box-magazine bolt-action firearm, the combination with a receiver having a cylindrical bolt-chamber and a transverse ejecting and loading opening intersecting the forward end thereof, of a self-contained magazine-holder adapted to be introduced into and removed from the gun as a unitary structure and fastened to the lower face of the receiver, a trigger-guard having its forward tang formed with an opening for the

passage of the magazine, and a cartridge-platform fitted into the forward end of the bolt-chamber, having an opening for the reception of the upper end of the box-magazine and forming a horizontal floor flush with the upper end of the magazine for the manipulation of single cartridges thereupon.

In testimony whereof I have signed this specification in the presence of two subscribing witnesses.

THOMAS C. JOHNSON.
